(57) **CLAIM**

The ornamental design for a combined flea and mosquito trap, as shown and described.

DESCRIPTION

FIG. 1 is a front perspective view of a combined flea and mosquito trap, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the combined flea and mosquito trap in an open state;

FIG. 10 is a front perspective view, showing the combined flea and mosquito trap with non-claimed portions removed for clarity of the disclosure; and,

FIG. 11 is a top view of the combined flea and mosquito trap according to FIG. 10.

The broken lines in the drawings illustrate the portions of the combined flea and mosquito trap, which form no part of the claimed design.

1 Claim, 11 Drawing Sheets
